OLIVER D. JOHANTGEN, OF CHICAGO, ILLINOIS, ASSIGNOR, BY MESNE ASSIGNMENTS,
TO VICTOR ADDING MACHINE CO., OF CHICAGO, ILLINOIS.

CARRIAGE MECHANISM FOR COMPUTING-MACHINES.

1,301,942.

Specification of Letters Patent. Patented Apr. 29, 1919.

Application filed May 29, 1916. Serial No. 100,531.

To all whom it may concern:

Be it known that I, OLIVER D. JOHANTGEN, citizen of the United States, residing at Chicago, in the county of Cook and State of Illinois, have invented a certain new and useful Improvement in Carriage Mechanism for Computing-Machines, of which the following is a full, clear, concise, and exact description.

10 My invention relates to improvements in computing machines and more particularly to carriage mechanism containing an accumulator or register, a platen and associated parts.
15 The mechanism illustrated herein is adapted for use with various different computing machines, the embodiment of the invention shown however, being particularly adapted for use with a ten key adding and listing machine illustrated in my co-pending application Serial Number 100,530, filed May 29, 1916. In said application a complete machine is illustrated, but the carriage mechanism and associated parts are not claimed
20 25 therein, being claimed in the present application.

To operate the machine, the operator depresses digit keys which position a single, combined accumulator actuating rack and type rack. The carriage is moved transversely across the machine with a step by step movement as the keys are actuated, whereby said rack is engaged successively by the accumulator wheels. The rack which is elevated, a variable amount by the depression of the different keys, turns the accumulator wheels and immediately thereafter is thrown rearwardly, striking against the platen to print the digits of the item, one at a time. In the embodiment of the invention herein illustrated, the keys may be depressed in the order corresponding to the natural order in which the digits are read, namely, from left to right. To permit this operation, the carriage is first manually moved to the right by the operator by means of a lever having keys thereon which determine the extent of said throw of the lever and hence stop the carriage in a position corresponding to the digit of the highest order. The carriage thereafter moves from right to left, step by step, to the position corresponding to the digit of the lowest order. If the machine is designed for operators accustomed to set the item backward,

that is, from right to left, the escapement mechanism and certain associated parts, may be reversed to permit operation of the carriage in the reverse direction.

In the accompanying drawings:

Figure 1 is a sectional elevation of a mechanism embodying the invention;

Fig. 2 is a top plan view thereof;

Figs. 3 and 4 show details of the subtraction key mechanism;

Figs. 5 and 6 show the accumulator and carrying mechanism in two different positions;

Fig. 7 is a top plan view of the mechanism in the lower part of the carriage.

Fig. 8 is a perspective view of a bell crank lever;

Fig. 9 is an elevation of a carrying plate; and

Fig. 10 is a top plan view thereof.

The accumulator carriage comprises a pair of side plates 10, 11, connected by various transverse members hereinafter referred to. A cover plate 12 is arranged at the front of the carriage which extends upwardly and partially over the top, being provided with a sight opening 13 through which the numeral wheels are visible. A bottom plate 14 is secured to said side plates, which are connected also at their rear by a transverse plate 15 carrying a stud 16 with a roller or pulley 17 mounted thereon. The carriage is supported at its rear end by means of said roller which rides along a cross rod 18 mounted at opposite ends in brackets 19 secured to the body 20 of the machine, said rod passing through openings 21 in the side plates 10, 11, and clearing the latter. The forward portion of the carriage is supported on a yoke 22 associated with suitable escapement mechanism located in the body of the machine, whereby said carriage is given a step by step movement across the machine. It is moved in the opposite direction by a manually operated setting lever 23, pivoted to the body of the machine at 24.

The accumulator or register is actuated by a rack 25 which rack is reciprocated or differentially positioned in a vertical direction by key actuated mechanism in the body of the machine. It may also be moved forward and backward slightly by a printing lever 26 which has sliding engagement therewith by means of a stud 27 and slot 28. Said lever has a projection 29 thereon arranged to

lock the carriage against movement and to perform other functions to be described. As the rack is being elevated, it is in engagement with some one of a series of idler wheels 30 constituting part of the accumulator, and mounted on a shaft 31, the latter being carried in a pair of arms 32 mounted to turn about a pair of studs 33, 34, secured to the side plates 10, 11. Said idler wheels, 10 as shown in Fig. 1, are in mesh with a series of gear wheels or totalizer wheels 35 mounted on a shaft 36. Each totalizer wheel has a numeral wheel 37 arranged to turn therewith. Said numeral wheels are adjacent to 15 the previously mentioned sight opening. A series of register wheels 38 supported on a shaft 39 are also arranged in engagement with the totalizer wheels 35. If the arms 32 are swung downwardly through a small 20 angle, the idlers 30 will be moved out of mesh with the totalizer wheels 35 and moved into mesh with the register wheels 38. This latter is the subtraction position, in which rotation of the idlers 30 by the rack will be 25 communicated directly to the register wheels 38 thereby reversing the rotation of the register wheels and numeral wheels.

The carrying is effected by collars 40 each 30 having a single tooth 41 thereon, each collar being arranged to turn with one of the register wheels 38. Whenever one of said wheels completes its rotation, the tooth 41 engages a finger 42 constituting part of a substantially T-shaped carrying plate 43. 35 There are a series of such plates, one in each of the spaces between the wheels 38 and each is pivoted on a stud 44 on an arm 45 mounted on a shaft 46 and normally held in the position shown by a spring 46'. The 40 end of the finger 42 is cut away, as shown in Figs. 9, 10, the cutout part being pressed between the teeth of the adjacent register wheel; the one above the one shown in Fig. 1. The position of the plate 43 with respect to the arm 45 is maintained by a small rectifying lever 47 pivotally mounted on the arm 45 and held against the flat head of the T by a spring 48 as shown. Said T-plate tends to remain in the position shown but 45 when swung about its pivot 44 through a small angle by the carrying tooth 41, it advances the next wheel 38 an amount corresponding to one tooth, further rotation being prevented by the engagement of the 50 point 49 of the T with one of the teeth on said gear, (Fig. 6). The totalizer wheels 35, which are always in mesh with these register wheels 38, are thereby advanced by this carrying action. The angular movement of said finger is limited by the rectifying lever 47 which strikes a stop 49' on the arm 45. This prevents complete rotation of the T-plate. It will be noted that the operation is the same regardless of the direction of rotation of the gear 32, except that

the T-plate is moved in the opposite direction and the opposite corner 49 then acts as a holding pawl. The carrying device is therefore operative either for addition or subtraction.

The carrying action is very rapid since the finger 42 is pressed radially inward toward the center of the register wheels 38, the arrangement being similar therefore to a toggle. As long as said finger remains on the dead center, there is no carrying movement, but as soon as said finger is moved out of radial alinement by the carrying tooth 41, the spring 46' throws the plate 43 and the finger 42 rearwardly, thereby completing 80 the carrying movement begun by the tripping of the finger 42 by the tooth 41. The effect of the spring 48 on the rectifying lever 47 is to tend to restore the T-plate to normal position and to permit the finger to 85 act as a spring lock to resist rotation of the register wheels, when in normal position. Such return to normal position however, if permitted would rotate gears 30, 35, 38. Said rotation therefore is opposed by the 90 pawl 50 which is held in frictional engagement with the wheel 35 by the spring 51. Said T plates may be restored to normal position however, if the arms 45 on which they are mounted are moved forwardly. 95 Such forward movement is accomplished by a cross rod 52 carried by a pair of pivoted arms 53 which are pivotally mounted on the shaft 46 on opposite sides of the group of carrying devices. The lower ends of said 100 arms 53 are connected by a second cross bar 54. The forward movement of said cross bars is effected by means of a lever 55 which is pivoted about the stud 56 and carries a grooved roller 57, the latter engaging the 105 cross bar 54 and swinging the same forwardly as the lever 55 rotates about its pivot, (Fig. 7). Said lever is moved by a stud 58 which projects downwardly through a curved slot 59 in the bottom plate 14 of 110 the carriage. The lower end of said stud is received within a slot 60 in the carriage setting lever 23. Prior to the time the stud 58 reaches the end of the slot 59, the shoulder 60' on said arm engages a pin 61 on a 115 plate 62 which is mounted to reciprocate on the base plate 14 of the carriage. Said plate is guided by pins 63, 64 secured to said base plate and projecting through slots 65, 66 therein. It also has a notch 67 adapted to 120 receive the lower end of a latch hereinafter described. The general function of said plate 62 is to move the printing lever, 26 out of the notches 68 in the rear of the base plate 14. This removal unlocks the carriage which is otherwise locked against lateral movement by said lever and said notches. Movement of said lever moves the rack 25 rearwardly, thereby withdrawing it 125 from engagement with the idlers 30 whereby 130

the carriage may be moved laterally without interference between said rack and said idlers. As the carriage setting lever is moved laterally by the operator, the arm 55 is first swung to the limit of movement permitted by the slot 59 after which the carriage as a whole travels laterally.

In a machine where it is desired to enter the item by depressing the digit keys in their natural order, namely from left to right, and the carriage is therefore to be moved from right to left, the following mechanism is provided:

Denominational or order keys 70 are mounted on the carriage setting lever 23 and serve when depressed to act as stops and limit the throw of said lever and hence of said carriage. Said keys are normally held in uppermost position by springs 71. When any one is depressed and the lever swung to the right, the lower end of said pin engages the forward end of a stop lever 72 thereby swinging said lever about its pivotal support 73 mounted on the body of the machine. An arm 74 on said stop lever is swung forwardly and engages a toothed plate 75 mounted on the under side of the carriage, thereby positively locking the carriage and the lever against further movement. The carriage is thus swung to the position corresponding to the highest order of the item to be registered, and thereafter the depression of the digit keys operates the escapement mechanism, whereby the successive idler wheels 30 are brought into mesh with the rack *seriatim* until the carriage reaches its initial position.

If the machine is to be constructed to permit the item to be entered from right to left, the denominational keys 70 may be omitted and the escapement mechanism and setting lever reversed whereby the carriage may move from left to right as the operator depresses the digit keys, and may subsequently be restored to normal position by said lever or some other manually operated device.

To effect subtraction, the subtraction key 80 is pressed rearwardly. Said key is mounted on a stud 81 in the frame of the machine and also on a stud 82 mounted in a member 83, the latter being pivoted about the stud 84. Said studs 81, 82 pass through suitable slots 85, 86 in said key. A link 87 is also mounted on said studs and has a slot 88 at one end, a little shorter than the companion slot 85, and having a hole 89 in the opposite end. It also has a downwardly projecting lock 90. A latch 91 having the form of a bell crank lever is mounted adjacent said key on a stud 92, the lower end of said latch fitting within the notch 67 in the reciprocating plate 62 (Fig. 7). Said latch 91 has a lateral projection 93 thereon which is arranged in the path of a projection 94 on the subtraction key. The rear end of said

projection 94 is beveled, whereby as said subtraction key is pressed rearwardly, said bevel rides over the lateral projection 93 thereby rocking the latch and moving the plate 62 and the printing lever 26 to the rear, thus moving the rack 25 out of engagement with the idlers 30, which engagement would interfere with the swinging of said idlers to subtraction position.

Prior to the actuation of the subtraction key 80, the link 87 is in its forward position with its projection 90 in front of the lateral extension 93. This locks the member 83 against movement, thereby preventing accidental movement of the accumulator from addition to subtraction position, such as might be caused for example, if the rack were in engagement with the idlers. Before the subtraction key reaches the end of its rearward movement, the stud 82 is engaged by the end of the slot 86 rocking the member 83 and drawing the link 87 to the rear until its projection 90 is to the rear of the lug 93, at which time the accumulator gears have been moved to subtraction position. Simultaneously the projection 94 snaps over the lug 93 thereby permitting the plate 62 to restore the latch 91 to normal position, the subtraction key being thereby locked against return movement by the projection 93.

The spring 96 tends to hold the parts in addition position unless they are positively locked in subtraction position. After the item has been subtracted, the operator before setting up another item for addition, swings the carriage setting lever to one side as previously described, thereby moving the plate 62 to the rear, this movement serving to swing the latch 61 sufficiently to release the subtraction key 80 and to permit it and the link 87 to be restored to normal position. The restoration to addition position is therefore accomplished automatically. This automatic action prevents oversight on the part of the operator who might leave the machine set for subtraction, whereas he may intend to add the subsequent items.

The platen and ribbon feed mechanism may be of any suitable construction, the following mechanism being suitable for the purpose: The platen 100 is mounted on the shaft 101, which shaft carries also a ratchet 102 actuated by the pawl 103. Said pawl is secured to a plate 104 which is mounted on the shaft 105 and is connected to a link 106, the latter being connected at its opposite end to the cross bar 52 and drawn rearwardly by a spring 107. It will be seen that whenever the setting lever is operated, the platen is advanced by the pawl and ratchet one tooth. The reciprocating movement of the bar 106 also operates an additional pawl 108 and ratchet 109 for advancing the two color ribbon 110. The ribbon is mounted on the spools 111, 112, and is folded across guides

113. When the subtraction key is pushed inwardly, the guide is raised, being a part of the plate 114, which is connected to the member 83. This elevates the ribbon to present the red half to the printing lever. The roll of paper may be supported on suitable brackets, said paper being passed around the platen in the usual manner and held thereto by spring-pressed feed rolls 115.
- 10 It is apparent that many of the various mechanisms herein described are independent of other parts of the apparatus, and may be used in other combinations, or various equivalent devices may be substituted therefor. In general, the invention is not to be limited to the various details and relative arrangement of the parts specified, except where limitations appear in the appended claims.
- 20 I claim—
1. In a carriage mechanism, a series of accumulator wheels, a single actuating rack therefor, spring locks for said wheels, and means associated with said rack arranged to render inoperative the lock of each wheel as it is engaged by said rack.
  2. In a carriage mechanism, a series of accumulator wheels, a single actuating rack therefor, a plurality of pivoted supports each having a spring lock thereon arranged to lock said wheels, and a printing lever co-operating with said rack and arranged to throw it out of engagement with said accumulator, said lever being arranged to engage each of said pivoted supports as said rack moves into engagement with the corresponding wheel thereby rendering inoperative the corresponding lock.
  3. A carriage mechanism comprising a series of accumulator wheels, and a single actuating rack therefor, said carriage having a step by step movement to bring said rack, a lever co-operating with said rack and arranged to throw it into and out of engagement with said wheels, a series of pivoted arms arranged to be engaged by a projection on said lever when said rack is in engagement with the corresponding wheel, a rectifying lever pivoted to each of said arms, a finger on each of said arms normally held between the teeth of the corresponding wheel by said rectifying lever, and a spring for each arm, holding said parts in normal position, each arm being moved to withdraw said finger from its wheel by engagement therewith of said projection.
  4. A carriage mechanism comprising an accumulator and a platen, a reciprocable member having teeth on one side to engage said accumulator and type on the other side to strike said platen, a printing lever for guiding said rack and moving it from out of engagement with said accumulator toward said platen, means on said carriage for lock-
  - 5 ing it to said lever to prevent movement of said carriage, a pivoted lever having a loose connection with said carriage whereby it may move said carriage laterally after a certain initial movement thereof, and means 70 on said carriage co-operating with said lever during said initial movement to unlock it from said first lever.
  6. A carriage mechanism comprising a frame, a transverse member having slots 75 therein, a reciprocable rack, a printing lever associated therewith, said lever fitting within said slots to lock said carriage, a plate slidable with respect to said notches to unlock said carriage, an arm for moving said plate, a pin on said arm projecting through a slot in said member, and a pivoted lever for moving said carriage, said pin engaging said lever whereby the initial swing of the latter serves to unlock said carriage, and a 80 subsequent swing thereof to move said carriage.
  7. In an adding machine, a carriage containing an accumulator, a transfer mechanism and pivoted means on which said 90 mechanism is mounted, a single actuating rack for said accumulator, means for locking said carriage to said rack, and manual means for unlocking said carriage and subsequently moving the latter, said means 95 serving also to disengage said transfer mechanism from said accumulator.
  8. In a carriage mechanism, an accumulator consisting of idler wheels, numeral wheels and register wheels, transfer fingers 100 normally locking said register wheels, a rack normally engaging said idler wheels, and means co-operating with said rack and each of said fingers *seriatim* prior to the engagement of said rack with said idlers to 105 unlock said register wheels.
  9. A carriage mechanism comprising an accumulator consisting of suitable supporting rods, and a series of idler wheels, numeral wheels and register wheels mounted on 110 said rods, means pivotally supporting said idler wheels rod whereby said wheels may be moved into and out of engagement with said register wheels to provide for subtraction, means for manually moving said carriage 115 laterally, and means co-operating with said subtraction mechanism and said last means for restoring said mechanism to adding position after each manual adjustment of said carriage laterally.
  10. The combination with a carriage, of a support therefor, a carriage lever pivoted on said support, denominational keys on said lever and a stop lever on said support arranged to be engaged by said keys and to engage said carriage to limit the movement of the latter in accordance with the key selected.
  11. The combination with a carriage, of a bar on which one end of said carriage is sup- 130

ported, an escapement mechanism supporting the other end of said carriage, a pivoted lever for swinging said carriage, and denominational keys on said lever to determine the movement of said carriage.

11. In an accumulator mechanism comprising register wheels, a series of carrying fingers normally engaging said wheels, a rack arranged to engage the accumulator 10 wheels successively and means controlled by said rack for moving any finger out of contact with the wheel engaged by said rack.

12. In an accumulator mechanism comprising register wheels, a series of carrying 15 fingers normally engaging said wheels, a rack arranged to engage the accumulator wheels successively, a printing lever for said rack having a projection thereon, and arms arranged to be engaged by said projection, 20 said arms carrying said fingers out of engagement with said register wheels.

13. A carriage mechanism comprising an accumulator, a transfer mechanism operative either for addition or subtraction, supporting means for said transfer mechanism whereby it may be moved out of operative engagement with said accumulator, said transfer mechanism serving also to lock said accumulator against rotation when in operative connection therewith, a single rack arranged to engage the successive wheels of said accumulator, and means associated with said rack for moving it into and out of engagement with said accumulator, said means 30 serving to lock said carriage against movement when said rack is in engagement with any of said accumulator wheels and serving also to move said transfer mechanism out of operative engagement with the corresponding 35 wheels of the accumulator.

14. In combination, a series of numeral wheels, a supporting shaft therefor, gears mounted on said shaft, a second shaft having register gears thereon engaging said numeral 40 gears, a third shaft mounted eccentrically with respect to either of said first shafts, idler gears thereon arranged to engage either said numeral gears or said register gears, whereby a reverse rotation may be effected 45 to permit addition or subtraction, a rack arranged to engage said idler gears in succession, yielding means engaging said numeral gears to resist rotation thereof, carrying fingers constituting spring latches engaging

50 said register gears to normally hold all of said gears against rotation, and means rendered operative by the engagement of said rack with said idler gears for withdrawing said spring latches from operative relation 55 with said register gears to permit rotation of all of said gears, said spring latches after being moved to carrying position tending to return to normal position and thus to move said gears, said movement being resisted by 60 said yielding means, the resistance of the lat-

ter being overcome by said rack during the operation thereof.

15. In combination, an accumulator, having numeral wheels, a register having wheels in engagement therewith, idlers, a pivoted support therefor permitting engagement of said idlers either with said numeral wheels or with said register wheels to permit addition or subtraction, a rack turning said idlers in the same direction either for addition or 70 subtraction, a subtraction key for moving said idlers, a transfer mechanism associated with said register wheels and operative in either direction, a latch for locking said subtraction key in subtraction position, a movable frame on which said accumulator is mounted, means coöperating with said rack to lock said frame against movement, said latch serving to dis-engage said rack from 75 said idlers.

16. In combination, an accumulator, an actuator therefor, pivoted arms for changing the relative arrangement of the gears of said accumulator to permit addition and subtraction, a pivoted member for operating said 90 arms, a subtraction key having a loose connection with said member, a link also connected with said member and arranged adjacent to said subtraction key, and a latch co-operating both with said subtraction key and with said link, and serving to lock said mechanism in addition or subtraction position, said link insuring proper engagement and disengagement of said actuator and said 95 accumulator.

17. A carriage mechanism comprising a frame, a locking plate having slots therein, a reciprocating plate on said locking plate, studs on the former received within slots in the latter to guide its movement, a pivoted 100 arm on said locking plate having a shoulder, a pin on said reciprocating plate engaged by said shoulder to move said plate so as to cover said slots, a roller on said pivoted arm, an accumulator in said carriage having a 105 transfer mechanism, means associated with said transfer mechanism engaged by said roller for restoring said mechanism to normal position after operation thereof, and manually operable means for moving said 110 arm, said means serving to operate said mechanism and to move said carriage laterally.

18. In combination, an accumulator, pivoted arms for changing the relative arrangement of the gears of said accumulator to permit addition and subtraction, a pivoted member for operating said arms, a subtraction key having a loose connection with said member, a link also connected with said member and arranged adjacent to said subtraction key, a latch co-operating both with said subtraction key and with said link, and serving to lock said mechanism in addition or subtraction position, a carriage in which 115 120 125 130

said mechanism is mounted, and a manually operable lever for moving said carriage, said lever serving also to trip said latch and automatically restore said accumulator to addition position after each actuation of said lever.

19. A carriage mechanism comprising a frame containing an accumulator and a platen, said accumulator comprising register wheels and spring actuated carrying mechanism, a rack arranged to reciprocate between the two and engaging first said accumulator and then said platen, a single lever for moving said carriage laterally, said lever serving also to restore said carrying mechanism, and means actuated by said lever for moving said rack out of engagement with said accumulator during such movement of said carriage.

10 15 15

either said accumulator or said platen during such movement.

20. A carriage mechanism comprising a frame containing an accumulator and a platen, said accumulator comprising register wheels and spring actuated carrying mechanism, a rack arranged to reciprocate between the two and engaging first said accumulator and then said platen, a single lever for moving said carriage laterally, said lever serving also to restore said carrying mechanism, and means actuated by said lever for moving said rack out of engagement with said accumulator during such movement of said carriage.

25 30

In witness whereof, I hereunto subscribe my name this 27th day of May, A. D., 1916.

OLIVER D. JOHANTGEN.
